UNITED STATES PATENT OFFICE.

JAMES WESLEY SPAUR, OF CABLE, MONTANA.

RAILWAY-CAR.

1,098,989.

Specification of Letters Patent.

Patented June 2, 1914.

Application filed January 20, 1914. Serial No. 813,201.

To all whom it may concern:

Be it known that I, JAMES W. SPAUR, a citizen of the United States, and a resident of Cable, in the county of Deerlodge and 5 State of Montana, have made certain new and useful Improvements in Railway-Cars, of which the following is a specification.

This invention relates to railway cars, and one of the principal objects of the invention 10 is to provide a construction and arrangement of the cars whereby the car ends will be disposed at an oblique angle transversely of the track, and hence upon the occurrence of a collision, the cars will not tend to telescope as is a common occurrence with the 15 ordinary form of car, but by reason of the car ends being disposed in substantially parallel relation and obliquely with respect to the track, will tend to be thrown to one side 20 of each other as they come together by impact of the collision.

Another object of the invention is to provide a novel and advantageous interior arrangement particularly adapted to cars of 25 the type set out.

With these and other objects in view which will become apparent as the description proceeds, the invention resides in the construction, combination and arrangement 30 of parts hereinafter described and claimed, and illustrated in the accompanying drawing, in which like characters of reference indicate like parts throughout the several figures, of which,

35 Figure 1 represents a top plan view partly in section of a car, and portions of adjacent cars, constructed according to my invention, and Fig. 2 represents a side elevational view of the same, portions being shown in vertical section, as indicated by the broken line 2-2 of Fig. 1.

Referring more particularly to the drawing, 5 represents the side sills and 6 the end sills, which form a frame on which the car 40 is built, in the usual manner. The car is provided with end walls 7, which are preferably constructed of heavy steel and which extend from the roof to the end sills, and the end walls are disposed at an oblique 45 angle with respect to the track 8, and are provided with openings to form doorways 9, by which access may be had from one car to another; and the portion 10 of each end wall to one side of the doorway, and 50 on the longer side of the car end, is disposed at a slight angle to the opposite portion 11

of the end walls, and more nearly at right angles with respect to the track, so that in turning a sharp curve, there will be no danger of the car ends striking or binding 60 against the ends of adjacent cars, it being understood that the ends of each car are oppositely arranged, and that all the cars are formed alike so that the portion 10 of the end wall of one car, or that portion 65 which occurs at the longer portion of the car end is disposed opposite the portion 11 of the adjacent car.

The steps 12 are arranged oppositely and toward the center of the car from the end 70 walls 7, and between the steps at the longer portion of each car end, and portion 10 of the end wall of the car, is formed a compartment 13 which may be used as a smoking or toilet room. On the opposite side 75 of the steps from the end wall of the car, the partitions 14 occur, which are arranged transversely of the car and in alinement with each other, and form an opening in which door 15 is swung, whereby access to 80 the interior of the car may be had.

The doors 16 which are of usual construction, are provided for the doorways 17 in the sides of the car which lead to the steps.

The cars are coupled as at 18 in the usual 85 manner. Removably secured to the car platform in the door openings 9 by means of bolts 19 which project through the end sills 6, and provided with cotter pins 20, are plates 21, which project outwardly and lap 90 one over the other, as shown in Fig. 2, to provide a support for passengers in going from one car to another. The plates are disposed obliquely with relation to the track, and in parallel relation to the adjacent ends 95 of the cars, as shown. By this construction it is evident that should a collision occur, the obliquely disposed car ends coming together, would slide past or to one side of each other, so to speak, and would not tend 100 to telescope, as is a frequent occurrence in cars of the ordinary construction.

The ends of the cars are free from any obstructions or projections which might tend 105 to catch on the end of an adjacent car should a collision occur, and thus prevent the cars from sliding to one side of each other, except the couplings, which, should the force of the collision be great enough, would break, thus permitting the cars to be projected to 110 the sides of each other.

By utilizing the compartment 13 occur-

ring between the steps and the portion 10 of the end wall at the longer part of the car ends, the seating capacity of the car will not be reduced, as would be the case were this 5 space not taken advantage of.

Although I have described the preferred embodiment of my invention, I may desire to make such changes in the construction, combination and arrangement of parts there- 10 of as do not depart from the spirit of the invention and the scope of the appended claims.

I claim:

1. A railway car having its end walls oppositely arranged and disposed at an oblique angle transversely of a track and extending the width of the car, a portion of each end wall being disposed at an angle to the opposite portion, and more nearly at 20 right angles to the track, said end walls having door openings therein, said car being provided with a compartment adjacent the longer portion of each end, and steps arranged oppositely to each other and transversely of the car, and between the compartment and body portion of the car, said angularly disposed portions of the end wall lying in oblique angles to the track.

2. A car having its end walls oppositely arranged and disposed at an oblique angle transversely of a track, a compartment arranged adjacent each end wall and in the longer portion of the car ends, steps arranged transversely of the car and in advance of said compartment, and partitions

arranged on the opposite side of the steps from said compartment transversely of the car and forming a door opening, the end walls of said car being provided with door openings occurring on the longitudinal medial line of the car, the portions of the end wall forming one wall of the compartment, lying at an oblique angle relative to the track.

3. A car having its end walls throughout their width disposed at an oblique angle transversely of a track, said end walls having the portions thereof occurring at the longer portions of the car disposed at an angle to the portions of the end walls occurring at the shorter portions of the car ends, and more nearly at right angles to said track, and being somewhat less in length than said portions occurring at the shorter portions of the car ends, said portions being plane and extending the entire height of the car body.

4. A car having its end walls formed of heavy material and disposed at an oblique angle transversely of a track, said walls extending the width of the car and having a portion thereof disposed at an angle to the remaining portion thereof, said portions being plane, said end walls being free from obstructions on their outer faces.

JAMES WESLEY SPAUR.
